CLAIM

The ornamental design for an agricultural vehicle, toy and/or replica thereof, as shown and described.

DESCRIPTION

FIG. 1 is a perspective view of an agricultural vehicle, toy and/or replica thereof according to our new design

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The dashed lines in the figures depict environment subject matter that forms no part of the claimed design.

1 Claim, 6 Drawing Sheets
